FIG. 4.

UNITED STATES PATENT OFFICE

THOMAS TWADDEL ALLEN, OF PHILADELPHIA, PENNSYLVANIA, ASSIGNOR TO SENTRY SAFETY CONTROL CORPORATION, OF PHILADELPHIA, PENNSYLVANIA, A CORPORATION OF DELAWARE

UNITARY SAFETY DEVICE FOR MOTION PICTURE PROJECTING MACHINES

Application filed June 18, 1928. Serial No. 286,376.

This invention relates to unitary safety devices for motion picture projecting machines and has for its especial object the mounting of such devices in the mechanism 5 housing of a motion picture machine such for instance as the "Motiograph".

In the motion picture machine art, various safety devices have been developed for the prevention of fire, the film being of such 10 a nature that an excessive amount of heat thereon will cause its ignition and oftentimes serious injury to the apparatus and to the operator in charge of the same. The mounting of these devices has given the manufacturers thereof not a little concern since 15 the projecting machines are usually produced independent of the safety devices, the latter being applied to the machines either at the time of, or after, installation.

One of the objects of this invention is to provide a unitary mounting for safety devices for motion pictures whereby the said devices will be completely enclosed in the mechanism housing of the projecting machine.

Another object is to provide a mounting whereby these safety devices may be housed in a more economical and facile manner.

According to the invention the unitary 30 device, which includes a plurality of safety switches and means for operating the same, is provided with standards for fastening the same to the framing plate of a motion picture machine and is so constructed and the parts so arranged that it can be applied to a conventional motion picture machine, such as the "Motiograph" as a unit and without disturbing any of the standard parts thereof.

The drawings illustrate an embodiment of the invention and the views therein are as follows:—

Figure 1 is a perspective view of the framing compartment of a "Motiograph" projecting machine and shows the improved unitary safety mounting incorporated therein,

Figure 2 is a fragmentary top plan view of the mounting partly in section with the safety devices applied thereto,

Figure 3 is a front view of the same,

Figure 4 is a rear view thereof, and Figure 5 is an end view looking in the direction of the arrow A in Figure 4 and with the safety devices removed.

The mounting 11 has a hole 12 through the 55 same whose edge is ribbed as at 13 to provide sufficient strength to the mounting which is ordinarily made of cast iron or steel. This hole is for the purpose of admitting a 60 centrifugal member 10, which is shown in position in Figure 1, and whose function is to operate a fire shutter (not shown) in a "Motiograph" projecting machine. Integrally formed with the mounting is a standard or foot 14 provided with a hole 16 65 through which a screw 17 fastens the same to the framing plate 18 of the conventional "Motiograph". On the other side of the mounting is a semibored hole 19 which is 70 counterbored as at 20 to provide means for 75 fastening the mounting as shown by the screw 21 in Figure 1.

The upper portion of the mounting is held in place by means of a bolt 22 having an 75 enlarged portion 23 and which is held against one of the shoulders of said enlarged portion by a nut 24. The other enlarged shoulder fits against the framing plate and is held against the same by a nut 26 bearing against a pad 25 on the said framing plate. 80 This bolt has a reduced extension 27 which is adapted to act as a stop for a limiting plate 28 on a switch actuating device 29 mounted on shaft 30 which extends through a sleeve 31 secured in the socket 32 on the 85 mounting by the set screw 32a.

This shaft 30 is adapted to operate a film switch 33 such as shown in a co-pending application of Thomas T. Allen, one of the applicants herein, and John Francis Adams, 90 filed October 12th, 1927, Serial No. 225,807, issued as Pat. No. 1,803,087 on April 28, 1931, and is particularly illustrated in Figure 3 in the drawings of said patent.

The limiting plate 28 is fastened by screws 95 or rivets 34 to the swivel block 36 through which the shaft 30 extends and the curved loop plate 35 of the switch actuating device 29 may also be fastened to the other side thereof by the same bolts or rivets. A set 100

screw 37 secures the swivel block to the shaft.

A bent rod is also secured in the swivel block and extends longitudinally through the same by the portion 38 and has a downwardly extending portion 39 and a bent end 41 while its portion 38, after passing through the swivel block, is bent over into a slot 42 and held therein by a washer 43 secured by a screw 44.

10 This particular kind of switch actuating device, while differing materially in detail from what is shown therein, is incorporated in a co-pending application filed by Joseph E. Cohen, on July 9th, 1927, Serial No. 204, 15 455, issued as Pat. No. 1,763,922 on June 17, 1930.

At the lower left hand corner of the mounting or bracket 11 there is provided a rearwardly extending arcuate wall 46 which 20 terminates in a right angular portion 47 having a lug 48 for receiving the shaft 49 of a centrifugal dowsler switch 51. This centrifugal dowsler switch is shown and described in a co-pending application of Thomas T. Allen, applicant herein, and John Francis Adams, filed December 13th, 1927, Serial No. 239,622, issued as Pat. No. 1,809,816 on June 25, 1931.

In the instant application, the centrifugal 30 mechanism of this switch is provided with a pinion 52 formed preferably of graphite impregnated bakelite or some other noiseless material and this pinion is meshed by an idle gear 53 which is mounted on a shaft 54 which 35 extends through the lug 56 on the rear of the mounting and provided at each end of the same with necessary reduced screw portions 55. Each of the screw portions are provided with washers 57 and nuts 58 so 40 that the shaft may be properly positioned in the mounting to provide a bearing limit for the gear without binding the same.

At a convenient place on the bracket there 45 is provided a terminal or splice box 59 where the necessary electrical connections are made and the same insulated in the proper manner.

Leading from the centrifugal switch 51 is a cable 61 which is secured in place on the mounting by a clip 62. The terminal box is 50 provided with a cover 63.

The switch 33, terminal box 59 and centrifugal switch 61 are all enclosed within the mechanism housing when the side cover (not shown) is placed thereon and the idle gear 55 meshes with one of the gears of the film feeding mechanism so that when said mechanism is operated, the switch 53 will operate to centrifugally open its contact so that the motor circuit may be used for operating the 60 shutter mechanism.

The uses of the several switches described herein are in each case fully explained in the application referred to hereinbefore in connection with the same.

65 The mounting provides a unitary struc-

ture which carries the centrifugal dowsler switch, film switch and curved loop plate, and the entire mechanism may be quickly and conveniently incorporated in a Motionograph without the removal or substitution of 70 parts.

Of course the mounting illustrated may be modified in various ways without departing from the invention herein set forth and hereafter claimed.

75 The invention is hereby claimed as follows:—

A unitary mounting for cooperative elements for actuating a safety device for a motion picture projecting machine, comprising a cast metal member spaced from and secured to the framing plate, a shaft supported at one end in said member for mounting a film switch thereon, a hood having a bearing for mounting the rotatable part of 80 a centrifugal switch, and means for mounting an idle gear for meshing with said rotatable part and an operative gear of the film feeding mechanism.

85 In testimony whereof I have signed my name to this specification.

90 THOMAS TWADDEL ALLEN.
